UNITED STATES PATENT OFFICE.

FRANKLIN S. GRAY AND THOMAS J. FLANAGAN, OF TULSA, OKLAHOMA.

PUMP.

1,177,860.

Specification of Letters Patent.

Patented Apr. 4, 1916.

Application filed February 18, 1915. Serial No. 9,215.

To all whom it may concern:

Be it known that we, FRANKLIN S. GRAY and THOMAS J. FLANAGAN, citizens of the United States, residing at Tulsa, in the county of Tulsa and State of Oklahoma, have invented certain new and useful Improvements in Pumps, of which the following is a specification, reference being had therein to the accompanying drawing.

10 The present invention relates to improvements in pumps, particularly the class known as double-acting piston operating pumps, the object being to provide a construction embodying the use of a minimum 15 number of parts and the assembling of these parts in a very compact form.

A further object of the present invention is the construction of a pump having a body proper composed of a single casing provided 20 with a cylinder, and a series of inlet and outlet ducts or ports arranged within the casing and in communication with the cylinder.

A still further object of the invention consists in the arrangement of an inlet and outlet 25 port at each end of the pump body, these ports at their outer ends being provided with suction controlled inlet and outlet valves and having all these valves mounted in the top of the pump body and opening 30 upon the outside of the casing. We also arrange these valves in the same horizontal plane whereby access to all the valves can be had, when it is desired to grind or replace the same, by the removal of a valve 35 cover mounted on top of the casing and adapted to inclose all valves.

Our invention also comprehends the use 40 of a particular form of valve cover adapted to inclose the inlet and outlet valves, the cover being provided in its under face with a series of pockets overlying the valves and spaced apart by means of division walls which have a water-tight connection with the top of the body, the pockets forming 45 reservoirs for the fluid during the operation of the piston whereby a continuous stream passes through the discharge ducts in view of the fact that the ports leading to the reservoirs or pockets are of greater capacity 50 than the discharge ducts leading from the pockets, which allows an accumulation of a small amount of fluid in the pockets between the strokes of the piston so that the stream discharged from the pump 55 is at all times constant without objectionable back pressure.

The invention also embraces the particular construction of end plates for the bore in the casting constituting the cylinder, which plates are outwardly bowed and so 60 constructed and attached to the cylinder as to be interchangeable from one side of the bore to the other.

Referring to the drawings: Figure 1, is a vertical sectional elevation of a pump constructed in accordance with our invention. Fig. 2, is a plan view of the same with the cover plate removed, and Fig. 3, is a vertical cross section through the body portion thereof.

With reference to the drawings wherein like numerals indicate corresponding parts, 70 1 designates the body or casing of the pump provided at its lower end with extensions 2 and 3 which constitute the legs or support 75 for the body.

Intermediate the top and bottom portions of the pump body is a longitudinally extending bore 4, representing the pump cylinder and adapted to house a reciprocating 80 piston 5, which is of the ordinary construction and is reciprocated by the piston rod 6 in any desired manner. The bore of the cylinder is closed at each end by inclosing plates 7 and 8; these plates being outwardly 85 bowed intermediate their ends to provide passages 9 and 10 between the ends of the cylinder and the plates, the purpose of which will be hereinafter described. In order to prevent any leakage of the fluid 90 through the plates 7 and 8 during the operation of the pump, we provide packing rings 11 and 12 of felt or any other suitable material between the ends of the pump body and the inclosing plates. Screws 13 and 14 95 are shown as the means for retaining these plates in position, but it will be readily seen that any other suitable fasteners may be used. The plate 8 is provided with an aperture 15 for the passage of the piston rod 100 6 and is also provided with an exterior flange 16 extending around the aperture to carry a suitable rod packing 17 held in place by a cap 19.

In the lower portion of the pump body 105 intermediate its ends is a fluid inlet port 20, this port extending a slight distance within the body at right angles to the cylinder and at its end provided with a pair of feeding ports or ducts 21 and 22. These ducts or 110 ports extend upwardly through the body and incline toward their ends from where

they lead in a direction at right angles to the upwardly extending portions 21 and 22, as indicated by the numerals 23 and 23', to the top of the casing, as shown in Fig. 1. 3 The object of forming the ports with these curvatures is to enable the ducts or ports to lead to the feeding valves which are directly over the cylinder and at the same time allow the upwardly extending portion of the port 10 to be positioned on one side of the cylinder.

Arranged in the head of the pump body or casing and positioned in the outlet portions of the feeding ducts or ports are inlet valve supporting members 24 and 25 adapted 15 to have a screw threaded connection with the feeding ports and supporting the inlet valves 26 and 27 of the usual construction and actuated by the suction caused when the piston is reciprocated. These inlet 20 valves are placed intermediate the outlet valves 28 and 29 supported in outlet ducts 30 and 31 by the valve supporting members 32 and 33, the inlet and outlet valves all being arranged in the same horizontal plane 25 and all opening exterior of the top of the pump body or casing.

Arranged on each side of the inlet valves are the feeding passages 34 and 35 leading downwardly through the body and communicating 30 with the ports 36 and 37, which ports are positioned above and are parallel with the cylinder establishing communication between the inlet and outlet valves and the cylinder through the passages 9 and 10 35 formed by the bowing of the inclosing plates 7 and 8. Discharge ducts 38 and 39 in the top of the pump body arranged on one side of the outlet valves 28 and 29, are provided to carry the fluid to the main discharge 40 port 40. These discharge ducts lead a slight distance downwardly through the body and then upwardly with the cylinder joining intermediate the ends of the block with the discharge port 40. The port 40 is of greater 45 diameter than the discharge ducts and is positioned in the pump body opposite the inlet port.

A cover 41 adapted to overlie the valves and the inlet and discharge ducts is provided 50 in its under face with a series of horizontally arranged pockets 42 separated by the spacing posts 43. The spacing posts 43 carry suitable packing 44, thereby forming 55 water-tight pockets preventing any leakage of the fluid held in these pockets during the operation of the pump. The top is preferably held in place by a series of screws 45 passing through the spacing posts and into engagement with the top of the pump body 60 or casing. The provision of the water pockets over the valves and the inlet and outlet ducts 34, 35, 38 and 39, respectively, enables the pump to maintain a constant discharge stream in view of the fact that the 65 outlet ports 30 and 31 are of greater

diameter than the discharge ports 38 and 39 which allows a small amount of liquid to accumulate in the pockets during the operation of the pump so that between the strokes of the piston the liquid which is accumulated in the pockets will then discharge through the discharge ducts thereby maintaining the discharge stream constant at all times during the operation of the pumps. 70

The arrangement being as described, the 75 operation of the pump is as follows. With the piston moving from left to right the suction created behind the piston will cause the closing of the valve 28 and the opening of the valve 26 thereby allowing the water to 80 pass into the pocket 42 and through ports 34 and 36 into the space behind the piston. At the same time the water in front of the piston will be forced through the passage 37, a small amount of the fluid passing 85 through port 35 into pocket 42 closing the valve 27, the remainder of the charge going into the port 31 through the valve 29 and into pocket 42 from where it is carried away by the discharge duct 39 to the discharge outlet. From the operation it will be readily seen that we have provided a pump having 90 an inlet and outlet valve at each end of the pump body or casing and when the inlet valve on one side of the casing is in operation the outlet valve is closed at the same time the outlet valve on the opposite side of the casing is open and the inlet valve closed.

Many modifications in structure and arrangement of parts are of course possible, hence we do not desire to be limited to the precise structure and arrangement herein described. 95

We claim:—

1. A pump comprising a body composed of a casting having a central bore therein constituting a cylinder, a piston within the cylinder, the said casting having a bifurcated port leading from the bottom thereof, upwardly through the body, and then extending in a direction at right angles to the upwardly extending part to the top of the casting, a pair of outlet ports in the body extending downwardly therethrough and communicating with the cylinder, all of said ports being arranged at substantially the center of the casting and in the same horizontal plane, and a series of suction controlling valves arranged at the outer portion of each port. 100

2. A pump comprising a body composed of a single casting having a central bore therein constituting a cylinder, and outwardly bowed interchangeable inclosing plate at each end of the cylinder, the body having a bifurcated inlet leading from the bottom thereof to the top intermediate its ends and a pair of outlet ports extending 110 downwardly through the body and commu- 120

nicating with the cylinder, all of said ports being arranged in the same horizontal plane and at their upper ends being controlled by suction actuated valves, substantially as described.

3. A pump comprising a body composed of a single casting having a central bore therein, constituting a cylinder, the casting having inlet ports extending upwardly from the bottom thereof intermediate its ends and then in the direction at right angles to the upwardly extending portions to the top of the body, and a pair of outlet ports arranged in the body and leading downwardly therethrough and communicating with the cylinder, all of said ports being located at

substantially the center of the body and being controlled by suction actuated valves, the said body near one side thereof having relatively small discharge ducts leading 20 therethrough to a main discharge port arranged in the center of the body, substantially as described.

In testimony whereof we hereunto affix our signatures in the presence of two witnesses. 25
